UNITED STATES PATENT OFFICE.

JOSEPH J. ST. WRBA, OF HOUSTON, TEXAS.

HYDROCARBON-BURNER.

1,347,920.

Specification of Letters Patent.

Patented July 27, 1920.

Application filed December 19, 1919. Serial No. 345,977.

To all whom it may concern:

Be it known that I, JOSEPH J. ST. WRBA, a citizen of the United States, residing at Houston, in the county of Harris and State 5 of Texas, have invented certain new and useful Improvements in Hydrocarbon-Burners; and I do hereby declare the following to be a full, clear, and exact description of the same, reference being had to the accompanying drawings, forming part of this 10 specification.

This invention relates to improvements in hydrocarbon burners, its object being to provide an inexpensive apparatus in which refined oil or heavy crude oil can be utilized 15 as fuel.

In the accompanying drawings—

Figure 1 is a front plan view, one half 20 of the apparatus being shown in section,

Fig. 2 is an end view.

As illustrated in the drawings the apparatus comprises a base in the form of a pan 1, on which is mounted a retort 2, and 25 positioned immediately above the retort is a reservoir 3, from the opposite ends of which a pair of pipes 4 extend. The pipes 4 are turned downwardly and then inwardly toward the retort 2 at which point 30 their end portions are bent upwardly so that they are in close proximity to both the retort and the reservoir. The retort 2 is preferably spherical and the reservoir cylindrical, the latter being of sufficient length 35 to extend over and beyond the retort, thus permitting the flame which issues from orifices 6 formed in caps 5 which close the bent up ends of pipes 4, to impinge against both the retort and the reservoir. The in-

terior diameter of pipes 4 is made as small 40 as possible in order to prevent the cooling off of the gases while passing therethrough, thus increasing the efficiency of the apparatus.

Oil is supplied from any suitable source 45 (not shown) through piping 7, 9 and a duct 10 formed in pan 1 to the retort 2 where, due to the heat applied to the retort, it is 50 transformed into gas. The generated gases 55 pass from the retort through an outlet 14 to the reservoir 3 thence through pipes 4 to the orifices 6 where they are burned for continuing the generation of gas and for heating the reservoir and any desired object, 60 the latter being supported immediately 65 above the reservoir in any suitable manner.

Preferably strainers, indicated at 12 are placed over the inlet and outlet openings of the retort. The retort is also filled with a quantity of gravel 11 which has the effect 60 of straining the fluid and assisting in heating the same.

After the body of gravel becomes heated the oil passing through the center of the retort comes in contact with the heated 65 gravel so that it is heated directly and the oil that comes in contact with the walls of the retort is vaporized by heat derived from said walls. In this manner practically every portion of the oil passing through the retort 70 comes directly in contact with a heated body, thus increasing the heating capacity of the retort which must, of necessity, be of small size to permit the reservoir to extend beyond it so that the flame may impinge against 75 both the retort and reservoir as heretofore pointed out.

To prevent back-flow of the generated gases in case of high pressure in reservoir 3, a check valve 8 is interposed in the piping 80 7, 9, and to regulate the flow of oil a needle valve 15, is also placed in said piping.

When the apparatus is to be used the needle valve is opened and a small quantity of oil is poured in pan 1, and ignited. The 85 heat from the burning oil in the pan will start the generation of gas in the retort which will flow through the path above described to the orifices 6 where it will be ignited. The burning of the gas at the 90 orifices will continue the generation of gas in the retort and heat the reservoir 3 and at the same time the heat derived from the flames may be utilized for any desired purpose. 95

What I claim is:

1. A hydrocarbon burner comprising an elongated cylindrical reservoir, a retort positioned immediately below and communicating with said reservoir, means 100 within said retort for straining and imparting heat to the hydrocarbon, means for supplying hydrocarbon to the retort and pipes leading from the opposite ends of the reservoir, the outer ends of said pipes being positioned immediately below the reservoir and adjacent to the retort, there being an orifice in the end of each of said pipes to permit the passage and ignition of the generated gas. 105

2. A hydrocarbon burner comprising an elongated reservoir, a spherical retort posi-

- tioned immediately below and communicating with said reservoir, the diameter of the retort being considerably less than the length of the reservoir whereby the bottom 5 of the reservoir is exposed throughout practically its entire length, means for supplying hydrocarbon to the retort and pipes leading from the ends of the reservoir and having orifices in their outer ends, said 10 outer ends of the pipes being so positioned with respect to the retort and reservoir that flames issuing from said orifices will impinge against said reservoir and retort.
3. A hydrocarbon burner comprising an 15 elongated reservoir, a spherical retort positioned immediately below and communicating with said reservoir, the diameter of the retort being considerably less than the length of the reservoir whereby the bottom 20 of the reservoir is exposed throughout practically its entire length, means for supplying hydrocarbon to the retort, means within the retort adapted to filter the hydrocarbon and to conduct heat thereto, pipes leading 25 from the ends of the reservoir and having

orifices in their outer ends, said outer ends of the pipes being so positioned with respect to the retort and reservoir that flames issuing from said orifices will impinge against said reservoir and retort. 30

4. A hydrocarbon burner comprising an elongated reservoir, a spherical retort positioned immediately below and communicating with said reservoir, the diameter of the retort being considerably less than the 35 length of the reservoir whereby the bottom of the reservoir is exposed throughout practically its entire length, pipes leading from the ends of the reservoir and having orifices in their outer ends, said outer ends of the 40 pipes being so positioned with respect to the retort and reservoir that flames issuing from said orifices will impinge against said reservoir and retort, and a base for supporting the retort and reservoir, said base 45 having a concave upper surface and a duct therein through which hydrocarbon is supplied to the retort.

JOSEPH J. ST. WRBA.
